CLAIM

The ornamental design for a beverage dispenser with illuminable element, as shown and described.

DESCRIPTION

FIG. 1 is a top, front, right side perspective view of a beverage dispenser with illuminable element showing our new design;

FIG. 2 is a front elevation view thereof;

FIG. 3 is a right side elevation view thereof;

FIG. 4 is a top plan view thereof;

FIG. 5 is a rear elevation view thereof;

FIG. 6 is a left side elevation view thereof;

FIG. 7 is a bottom plan view thereof; and,

FIG. 8 is a top, rear, left side perspective view thereof. The broken lines represent portions of the beverage dispenser with illuminable element that form no part of the claimed design. The alternating long and short lines indicate light emanating from the illuminable element.
